UNITED STATES PATENT OFFICE.

SIMON FLORSHEIM, OF CHICAGO, ILLINOIS, ASSIGNOR OF ONE-HALF TO MICHAEL ALTMAN, OF CHICAGO, ILLINOIS.

COIN-RECEPTACLE.

986,158.

Specification of Letters Patent. Patented Mar. 7, 1911.

Application filed February 9, 1910. Serial No. 542,875.

To all whom it may concern:

Be it known that I, SIMON FLORSHEIM, a citizen of the United States, and a resident of Chicago, in the county of Cook and State 5 of Illinois, have invented certain new and useful Improvements in Coin-Receptacles; and I do hereby declare that the following is a full, clear, and exact description thereof, reference being had to the accompanying 10 drawings, and to the letters of reference marked thereon, which form a part of this specification.

This invention relates to improvements in coin receptacles, and more particularly to 15 a coin receptacle adapted to be attached to the upper free edge of the palm of a glove, or to the edge of an exposed pocket to a button-hole or otherwise.

The invention consists of the combination 20 of parts hereinafter described and more particularly pointed out in the appended claims.

In the drawings:—Figure 1 is a perspective view of a gloved hand, showing my improved coin receptacle in position for use. Fig. 2 is a perspective view of the coin receptacle on an enlarged scale. Fig. 3 is a 25 vertical section through Fig. 2 on the line 3—3 thereof. Fig. 4 is a vertical section 30 through Fig. 3 on the line 4—4 thereof. Fig. 5 is a transverse section through Fig. 3 on the line 5—5 thereof.

Considerable trouble and annoyance is experienced by one wearing gloves, particularly a man, who generally carries his 35 change loose in his pockets, in taking from his pocket or from his pocketbook, small coins such, for example, as five cent pieces for the payment of carfare and the like. 40 This trouble is especially apparent when riding on the so-called "pay-as-you-enter" street car, when the fare must be obtained readily and quickly in order that the platform may not be obstructed by passengers 45 hunting for their change, while others are waiting to get on the car.

The object of my invention is to prevent such trouble and annoyance and to this end I provide a coin receptacle adapted to contain 50 one or more coins of like denomination or size which may be worn unobtrusively and without inconvenience in a readily accessible location, and from which a single coin may be quickly and easily extracted 55 without removing either glove.

My improved coin receptacle is of cheap and economical construction and is adapted to be attached to the upper free edge of the palm of a glove, as shown in Fig. 1, or to the edge of an exposed pocket. 60

My improved device comprises a pocket member A, and a clasp member B, by means of which the device, as a whole, is secured in place. In its preferred form the pocket member A consists of a back wall A¹; side 65 walls a a; marginal bottom wall portions a¹ a¹; and marginal front wall portions a² a², arranged parallel to the back wall A¹. The marginal front wall portions a² a² and the marginal bottom wall portions a¹ a¹ are 70 separated by a slot or opening a³, so as to expose the front face and the bottom edge of the coin or coins. The side walls a a are joined along their lateral vertical edges with the marginal front wall portions a² a², and with the back wall A¹, but are disconnected 75 therefrom toward their upper ends which are free and are bent inwardly, and then flared outwardly to form an elastic, restricted passage or throat C at the top of the 80 pocket member. The clasp member B is preferably in the form of an integral extension of the back wall A¹ of the pocket member, bent down against the rear face of said back wall. It is rounded at its lower end 85 and also made concave on the side next the back of the pocket, so that it may be readily inserted between the palm of the hand and the edge of the glove as shown in Figs. 1 and 4 where D indicates the glove and d that 90 part of it which lies between the clasp member and the rear face of the back of the pocket member.

My improved coin receptacle may be constructed to hold one or more coins. It is 95 preferably formed from a single piece of metal and may be manufactured at small expense. As indicated in Fig. 2, where the coins are shown in dotted lines, the receptacle is made large enough to contain two coins, 100 in this instance, five cent pieces. The side walls a a, where they are joined to the front and back walls, are separated by a distance slightly exceeding the diameter of the coin, while their upper free ends a⁴ a⁴, where they 105 most nearly approach each other, are separated by a distance slightly less than the diameter of the coin. It is thus apparent that when a coin has been pushed beyond the elastic restricted passage or throat between 110

said side walls, it will not fall out or be accidentally removed by contact with the clothing, since it will require some force to withdraw it through said restricted passage or throat. When it is desired to remove a coin from the receptacle the finger is inserted in the slot or opening α^3 between the marginal front wall portions of the pocket, and is engaged against the exposed 10 face of the coin and against its lower edge, whereupon the coin may be drawn through the restricted passage or throat C. If more than one coin is in the pocket, those nearer the back will be left therein ready for use 15 the next time. By making the bottom wall with marginal portions in the same manner as the front wall, the engagement of the finger with the lower edge of the coin is made possible, and this is particularly desirable 20 when the pocket contains more than one coin, since the outermost coin may be then withdrawn without pressing against it to such an extent, as to cause it to frictionally engage the coin behind it and thus draw the 25 second coin with it.

I claim as my invention:—

1. A coin receptacle comprising a pocket member adapted to receive one or more coins, and a clasp member adapted to removably 30 attach said receptacle in place, said pocket member having back, side, bottom and front walls, and having a restricted elastic throat

near its top adapted to engage the circumferential edges of a coin when the same is withdrawn from the receptacle, said throat 35 being otherwise open unobstructed, and said front and bottom walls being provided with a slot or opening, and said bottom wall acting as a stop to engage the circumferential bottom edge of the coin or coins at laterally 40 separated points.

2. A coin receptacle made from a single piece and comprising a pocket member adapted to contain one or more coins, and a clasp member located back of the pocket 45 member adapted to attach the receptacle in place, said pocket member having a back wall, marginal front and bottom wall portions separated by a slot or opening, and side walls, said side walls being free at their 50 upper ends and bent to form a restricted throat adapted to yieldingly engage the circumferential edges of a coin when the same is withdrawn from the receptacle, said throat being otherwise open and unob- 55 structed.

In testimony, that I claim the foregoing as my invention I affix my signature in the presence of two witnesses, this 4th day of February A. D. 1910.

SIMON FLORSHEIM.

Correction in Letters Patent No. 986,158.

It is hereby certified that in Letters Patent No. 986,158, granted March 7, 1911, upon the application of Simon Florsheim, of Chicago, Illinois, for an improvement in "Coin-Receptacles," an error appears in the printed specification requiring correction as follows: Page 2, line 36, after the word "open" the word *and* should be inserted; and that the said Letters Patent should be read with this correction therein that the same may conform to the record of the case in the Patent Office.

Signed and sealed this 28th day of March, A. D., 1911.

[SEAL.]

E. B. MOORE,
Commissioner of Patents.
